ARC PLASMA GENERATOR WITH STARTER
Thomas A. Barr, Jr., Robert F. Mayo, and Thomas G. Roberts, Huntsville, Ala., assignors to the United States of America as represented by the Secretary of the Army
Filed Jan. 18, 1965, Ser. No. 426,453
2 Claims. (Cl. 315—238)

ABSTRACT OF THE DISCLOSURE

An arc plasma generator with a spark-plug type starter. The starter has a vaporizable dielectric between its electrodes, and injects vapor from the dielectric between the arc electrodes of the generator. This vapor allows an arc to be readily struck between the electrodes of the generator.

The invention described herein may be manufactured and used by or for the Government for governmental purposes without the payment of any royalty thereon.

This invention relates to an arc plasma generator starter which is simple in nature and inexpensive.

Arc plasma generators are finding extensive use now in various aerospace research projects. An arc plasma can provide a high temperature, high velocity flow which is useful for testing missile nosecones, or may be employed for flame plating. The starting, or ignition of arc plasmas in prior art devices has been difficult.

An object of the present invention is to overcome the above difficulty.

Another object of the invention is to provide an inexpensive arc plasma generator starter.

A further object is to provide an arc plasma generator starter which is simple to construct.

A still further object is to provide an arc plasma generator starter which may be accurately timed in operation.

Yet another object is to provide means whereby a plurality arc plasma generator starters may be accurately and simultaneously activated.

Many arc plasma generators operate in a high vacuum and some means must be provided to form a conductive path through the vacuum before an arc can be established. In the past, this has been done by any one of several different ways. A high voltage, as from a Tesla coil, may be used to cause a spark discharge within the arc plasma chamber, which discharge provides a conductive medium through which the arc plasma may be established and maintained.

This scheme has the disadvantage that the high voltage from the Tesla coil can damage the insulators of the arc plasma chamber and may eventually allow conductive paths to form through the insulators.

Other ways in which the arc plasma may be started are by the use of an exploding wire or cap within the arc chamber or by the use of a piece of steel wool between the arc electrodes to provide a low resistivity path for starting. Each of these ways has the disadvantage of requiring manual reloading after each starting, and they are somewhat difficult to control in time. The present invention requires only occasional reloading, can be accurately timed and does not harm the arc chamber insulators.

Basically, the invention is a starter for an arc plasma generator, which starter employs the ablation of a dielectric plastic by a high voltage spark-discharge to produce a small-scale plasma discharge.

The invention may be understood by reference to the drawings, in which the same numerals are used to designate the same parts appearing in different figures wherein:

FIGURE 1 is a view, partly in section, of the starter in accordance with the invention;

2

FIGURE 2 shows the starter in position in the arc plasma generator schematic-section;

FIGURE 3 is a schematic diagram of a system for operating the starter of FIGURE 1; and

FIGURES 4, 5 and 6 each show schematic diagrams of alternate schemes by which the starter of FIGURE 1 may be operated.

Referring to FIGURE 1, numeral 10 designates a spark plug, of the type which may be used in automobile engines, but with the plug being modified in accordance with the invention. The type of plug used is that type having a center electrode 11 and center insulator 12 which extends beyond the threaded metal body 13 of the plug. The normal ground electrode (not shown) of the plug is ground or filed off and a plastic insert 14 is inserted around the center insulator 12. The numeral 12a designates the exterior extension of the center insulator 12, and 11a is the exterior extension of center electrode 11, to which high voltage lead 15 with insulating boot 15a is connected. The arc plasma generator metal housing wall is member 16, and member 17 is a noncorroding metal gasket inserted between the insert 14 and the bottom of a bore in which body 13 of the starter plug is screwed. A bore 18 passes between the electrode 11 and the interior of the housing 16. The insert 14, in the specific embodiment, is made of Lucite, but many other substances would be proper. Polyethylene or other linear polymers could be used, as well as Teflon and other fluorocarbon polymers. Other polymers or substances may be used, the requirements being: a dielectric which does not shatter readily under the electrical or other stresses developed in the starter, which is readily vaporizable by a spark discharge and which leaves no significant ash upon vaporization. Gasket 17 may be brass, copper, stainless steel, tantalum or some other noncorroding metal. The gasket is not absolutely necessary, but is convenient because it prevents wear on housing 16.

FIGURE 2 shows the spark plug assembly in place in the housing 16, with the set up of the arc plasma generator shown. The arc plasma generator is known in the art and consists of an anode 19 and a cathode 16 (the housing) surrounded by focusing electromagnets 21. Insulator 22 separates the electrodes 19 and 16. A high voltage from high voltage supply 23 is applied between the electrodes but is ordinarily insufficient to start an arc therebetween. High voltage supply 23 includes a high voltage terminal 23a connected to cathode 19, and a ground (negative) terminal 23b connected to housing member 16 (the anode of the generator). A sparking circuit 24, with a high voltage terminal 24a and a ground (negative) terminal 24b has its high voltage terminal connected to high voltage lead 15 by lead 27, and its ground terminal connected to housing member 16. The details of circuit 24 are shown in the dotted line box labeled 24 in FIGURE 3.

FIGURE 3 shows a high voltage supply 24c connected to a solenoid operated switch S₁. When in the position as shown, S₁ allows capacitor C to charge through conductor 25 and conductor 26. When moved by solenoid 29 through insulator 29a to its other position, switch S₁ allows the capacitor C to discharge through the spark plug 10 by way of conductor 28 and conductor 27. The inductance L acts as a choke and prevents a high voltage surge from appearing on the ground conductor 26 as the capacitor C discharges. Switch S₂ is a safety shorting switch for C and is normally closed when the device is not in use, and normally open when the device is in use. Terminals 24a and 24b correspond to like designated terminals in FIGURE 2. FIGURE 3 is drawn to show two spark plugs connected to the firing circuit, but obviously one, or more than two spark plugs could be connected to be fired simultaneously. With the arrangement as shown, the plugs are fired at substantially the same instant.

Referring again to FIGURE 2, when the spark plug fires, a portion of the plastic insert 14 is ablated and discharged as a plasma through the passage 18 into the interior of the housing 16. This plasma increases the conductivity of the space between the anode 19 and cathode 16, and allows an arc to ignite between them. Once such arc is started, the high voltage supply 23 is of sufficient voltage to maintain the arc.

FIGURE 4 shows a modified form of FIGURE 1, but with a thyratron being used to complete the discharge circuit for the capacitor C. Operation of the FIGURE 4 system is the same as that of FIGURE 3, except that switch S₃ is ganged to switch S₁ but is so arranged that S₃ closes after S₁ breaks but before it can make the conductor 28 contact. This last contact for S₁ could be omitted in this embodiment. The closure of S₃ applies voltage from battery B to the thyratron 30 to cause it to conduct.

FIGURE 5 shows a further modified form of the basic circuit of FIGURE 3. Capacitor C is charged through conductors 25 and 31 and, when switch S₁ is operated from right to left, discharges through conductors 25 and 32. Inductor L' acts as a choke to prevent a high voltage from appearing on conductor 33 when C discharges. The operation of the circuit is otherwise similar to the FIGURE 3 circuit.

FIGURE 6 shows a modified form of FIGURE 5 in which a thyratron 30' is used as a switch for applying the high voltage to the starters. The operation of the circuit is substantially the same as that of FIGURE 5, except that switch S₃ is ganged to switch S₁ and makes contact after switch S₁ opens but before S₁ can make with its alternate contact. If desired, such alternate contact could be omitted. When S₃ makes contact, voltage from battery B is applied to the grid of 30' and the thyratron conducts, allowing discharge of capacitor C.

In each of the embodiments of FIGURES 3, 4, 5 and 6, it should be noted that both electrodes of the spark plugs are at ground potential during the charging of capacitor C, except for the small voltage developed across L or L' during charging, such voltage being due to the IR drop across the finite resistances of the inductors.

While specific embodiments of the invention have been disclosed, other embodiments may be obvious to one skilled in the art.

While a modified automobile spark plug has been specifically described, other types of sparking plugs may be used, if the required specifications are met.

The high voltage power supplies 23 and 24 have been shown as separate, but could obviously be tapped from the same high voltage supply source. Also, the voltage of the

battery B could be tapped (with, for example, a voltage divider) from the same source as 23 and 24. If desired, a current limiter for the charging current of C could be provided, in any one of several known ways.

5 Solenoid 27 could be electrically, mechanically, hydraulically, pneumatically or manually operated to activate rod 29, and no specific means is shown for its operation.

Thytratrons 30 and 30' could be fired by a separate accurately timed device (not shown), if desired.

10 While a specific use has been described for this starter, it may find other uses, such as a blasting cap for explosives, or a vernier rocket for a space craft. The discharge from the starter could be used to cause a circuit 15 interruption in response to high voltage surge on the starter, and could be used as a circuit break and/or surge protector.

We claim:

1. An arc plasma generator having a housing with a 20 first space therein; a centrally disposed electrode penetrating said space, but insulated from said housing; a first high voltage source having a first ground terminal, connected to said housing and a first high voltage terminal, connected to said electrode, a starting device having an 25 outer electrode with a second space therewithin, and an inner electrode penetrating said second space, but insulated from said outer electrode; said other electrode connected to said housing, with a passageway between said spaces; a second high voltage source having a second 30 ground terminal, connected to said housing and a second high voltage terminal, connected to said inner electrode.
2. The starter of claim 1 in which the electrodes of 35 said sparking device comprise a first rod shaped electrode and a second coaxial cylindrical electrode surrounding said first electrode and in which said dielectric surrounds one end of said first electrode, except for a coaxial perforation of less diameter than the first electrode.
